UNITED STATES PATENT OFFICE.

CARL P. MILLER, OF FARGO, NORTH DAKOTA.

HAT-HANGER.

1,390,372.

Specification of Letters Patent. Patented Sept. 13, 1921.

Application filed July 24, 1920. Serial No. 398,606.

To all whom it may concern:

Be it known that I, CARL P. MILLER, a citizen of the United States, residing at Fargo, in the county of Cass and State of North Dakota, have invented certain new and useful Improvements in Hat-Hangers, of which the following is a specification.

This invention has for its object the provision of a simple, inexpensive and easily manipulated device which may be readily fitted to the top of a motor vehicle to support a hat above the heads of the occupants of the vehicle so that the hat will be secured against loss and the occupants of the vehicle will be subjected to no inconvenience or discomfort. The invention is illustrated in the accompanying drawings and consists in certain novel features which will be hereinafter first fully described and then particularly pointed out in the appended claims.

In the drawings—

Figure 1 is a perspective view of my improved device in its operative position;

Fig. 2 is a sectional elevation of the same. In the drawings, the reference numeral 1 indicates a portion of one of the bows of an automobile top. In carrying out my present invention, I employ a pair of mating clamping plates 2 which are constructed at one end with jaws 3 adapted to fit closely around the side portion of the bow 1 and be secured firmly thereto by set bolts 4 inserted through the clamping plates 2 and equipped with wing nuts 5 whereby when the nuts are turned home the jaws will be drawn toward each other and secured firmly upon the bow. The inner opposed faces of the jaws may, if desired, be lined with some soft material such as textile fabric, rubber or leather so that the use of the device will not mar the finish of the bow, as will be readily understood. As shown in the drawings, the clamping plates 2 project inwardly from the bow in a horizontal position and when in place are disposed close to the top of the bow. Fitted between the clamping plates is a wire or light rod 6 having its inner end doubled upon itself to fit around the upper fastening bolt 4, as shown most clearly in Fig. 2, and the upper corners of the plates 2 are indented slightly, as shown at 7, so as to aid in maintaining the said wire or rod 6 in its proper position. A bolt 8 is fitted through the clamping plates adjacent the upper inner corner thereof and is equipped with a wing nut 9 whereby the secure fasten-

ing of the parts will be assured. The outer end of the wire or rod 6 is doubled upon itself, as shown most clearly in Fig. 1, to provide a base ring 10 and arms or loops 11 radiating therefrom at intervals, the terminal of the rod being formed into an eye 12 engaged around the main portion thereof so as to prevent spreading of the base, as shown in Fig. 1 and as will be readily understood. Fitted about the bolt 8, between the clamping plates 2, is a latch consisting of a short strand of wire doubled upon itself to form an eye 13 engaging the bolt 8, as shown clearly in Fig. 2, and then extending from the bolt beyond the ends of the plate, as shown at 14, the ends of the wire strand being bent downwardly from the portions 14, as shown at 15, and offset, as at 16, to form holding seats. Beyond the seats 16, the ends of the wire are bent slightly outwardly, as shown most clearly at 17. The inner terminal 18 of the rod or wire 6 bears upon the under side of the eye 13 and serves as a spring retainer to resist downward movement of the latch. Pivotally mounted upon the lower bolt 4 is a supporting arm 19 which extends from said bolt between the clamping plates 2 and is adapted to pass through and be held by the seats 16 of the latch. Beyond the said seats, this arm 19 is bent downwardly in approximately a semi-circular form, as shown at 20, and is then carried upwardly, as shown at 21, and secured to the circular plate 22 upon the upper side of which are secured the cross arms or bars 23. The plate 22 is substantially equal in diameter to the base plate presented by the ring 10 and the arms or loops 11 while the bars 23 extend beyond the said plate 22 and are turned downwardly at the edge thereof to present resilient sustaining arms 24.

It is thought the manner of using the device will be readily understood from the foregoing description, taken in connection with the accompanying drawings. The device is intended, more particularly for holding ladies' hats and to that end the sustaining arm 19 is provided with the deep downwardly bent portion 20 which will accommodate the rim of the hat and pass under the same so that the plate 22 with the upstanding terminal arm 21 and the springs 24 may fit within the crown of the hat and support the same. The hat is placed over the sustaining arm with the springs 24 fit-

2

ting within the crown thereof and said arm is then swung upwardly against the upper base member at the outer end of the arm 6 so that the crown of the hat will be held firmly against the said base member and the hat thereby held out of the way of the occupants of the vehicle and secured against loss through being carried off under a high wind. It is to be particularly noted that the ring 10 and loops or arms 11 radiating therefrom present an open construction which will readily permit flowers, ribbons, feathers, or other decorations upon the hat to be easily disposed so that they will not be crushed or 15 otherwise damaged. When the arm 19 is swung upwardly with the hat thereon, it passes easily between the divergent terminals of the latch and into the space between the seats 16 by which it will be firmly engaged and the spring terminal 18 will bear 20 against the eye 13 with sufficient strength to resist dropping action of the latch and the arm. The device is exceedingly simple in construction and may be produced at a very 25 low cost and applied to any vehicle very easily and without the use of any tools or requiring any skilled labor.

Having thus described the invention, what is claimed as new is:

30. 1. A device for the purpose set forth comprising a support, an arm held by and extending from said support and provided at its free end with a base member to rest upon the crown of a hat, a sustaining arm pivotally fitted within the support below the 35 first-mentioned arm and constructed at its free end to engage within the crown of a hat and support the same against said base member, and a latch carried by the support 40 to engage under and sustain said pivoted arm.

2. A device for the purpose set forth comprising a pair of clamping plates a relatively fixed arm having an inner spring terminal housed between said plates and having its outer end expanded to bear upon the crown of a hat, a relatively movable arm supported by and between the plates below the first-mentioned arm and having its free 45 end constructed to pass under the rim of a

hat and fit within the crown of the same to hold the crown against the said expanded portion of the first-mentioned arm, and a latch between the plates mounted adjacent and engaged by the spring terminal of the 55 first-mentioned arm and constructed to engage under and sustain the said movable arm.

3. A device for the purpose set forth comprising a pair of clamping plates constructed at one end to engage around a fixed support, a plurality of bolts inserted through said plates, one of said bolts being disposed near the free ends of the plates, a relatively fixed arm doubled on itself around an upper bolt and projecting from between the free ends of the plates, the outer terminal of said arm being a flat open loop to bear upon the crown of a hat and the inner terminal thereof being resilient and disposed below and adjacent the bolt near the free ends of the clamping plates, a latch mounted on said last-mentioned bolt and projecting outwardly between the free ends of the clamping plates, the resilient terminal of 75 said arm bearing against said latch, and a said arm bearing against said latch, and a vertically swinging arm pivoted on a lower bolt and projecting from between the free ends of the clamping plates and constructed to engage within a hat crown and normally 80 engaged and held in raised position by the latch.

4. A device for the purpose set forth comprising a pair of clamping plates constructed at one end to engage around a fixed support, means for securing the plates about said support, a latch mounted between the plates near the free ends thereof and projecting beyond said ends, a relatively fixed arm projecting from the plates and having its inner portion extending between the latch and the upper edges of the clamping plates and terminating below and in contact with the end of the latch, the upper edges of the plates at their free ends being indented over 90 said arm, and a lower arm pivoted between the clamping plates and normally extending through and supported by the latch.

In testimony whereof I affix my signature.

CARL P. MILLER. [L.S.]
